[57] CLAIM

The ornamental design for a lamp or the like, as shown and described.

DESCRIPTION

FIG. 1 is a rear elevational view of a lamp or the like showing my new design;

FIG. 2 is a left side elevational view thereof, the right side being a mirror image;

FIG. 3 is a top plan view thereof;

FIG. 4 is a bottom plan view thereof;

FIG. 5 is a front elevational view thereof;

FIG. 6 is a rear elevational view of a second embodiment of my new design;

FIG. 7 is a left side elevational view thereof, the right side being a mirror image.

FIG. 8 is a front elevational view thereof;

FIG. 9 is a top plan view thereof; and

FIG. 10 is a bottom plan view thereof.
